DESIGN FOR A HYDRAULIC PRESS

Albert M. Ashman, Seal Beach, Calif.

Application March 23, 1946, Serial No. 127,832

Term of patent 14 years

(Cl. D63—1)

To all whom it may concern:

Be it known that I, Albert M. Ashman, a citizen of the United States, residing at Seal Beach, in the county of Orange and State of California, have invented a new, original, and ornamental Design for a Hydraulic Press, of which the following is a specification, reference being had to the accompanying drawing, forming part thereof.

Figure 1 is a front perspective view of a hydraulic press embodying my new design; and

Figure 2 is a side elevation of the press shown in Figure 1, the sides of the hydraulic press, not shown, have plain surfaces.

I claim:

The ornamental design for a hydraulic press, as shown and described.

ALBERT M. ASHMAN.
